Primary Examiner—Donald P. Walsh*Assistant Examiner*—Jeffrey Asch*Attorney, Agent, or Firm*—James F. Duffy[57] **CLAIM**

The ornamental design for hanger for fabric arts, as shown and described.

DESCRIPTION

FIG. 1 is a front, top, and left side perspective view of a hanger for fabric arts showing my new design;

FIG. 2 is a top plan view;

FIG. 3 is a right side elevational view; and,

FIG. 4 is a rear elevational view thereof.

FIGS. 2-4 have been shown on a reduced scale with respect to FIG. 1.
